UNITED STATES PATENT OFFICE

168,895

CANOPY

James E. Jones, Toledo, Ohio, assignor to The Hettrick Manufacturing Company, Toledo,
Ohio, a corporation of Ohio

Application September 25, 1952, Serial No. 21,585

Term of patent 14 years

(Cl. D88—3)

To all whom it may concern:

Be it known that I, James E. Jones, a citizen of the United States and a resident of Toledo, Lucas County, Ohio, have invented a new, original, and ornamental Design for a Canopy, of which the following is a specification, reference being had to the accompanying drawing, forming a part thereof.

In the drawing:

The support shown in broken lines is for illustrative purposes only.

I claim:

The ornamental design for a canopy, as shown and described.

JAMES E. JONES.
